SECTIONAL FLOOR

Charles Tramill, Kansas City, Mo.

Application April 20, 1933, Serial No. 666,991

9 Claims. (Cl. 20—6)

This invention relates to floors and more particularly to removable floors including platform-like sections that may be installed when wanted and disassembled for storage.

5 The principal objects of this invention are to interlock sections of removable flooring and to securely retain floor sections and supporting means in firm engagement when installed for enhancing the stability without reducing the 10 resilience of the floor.

10 Other objects of the invention will be apparent in the course of the following description of one form of apparatus embodying the invention and illustrated in the accompanying drawings where- 15 in:

Fig. 1 is a perspective view of a floor comprising supporting members and surfacing sections constructed in accordance with this invention, the board surface being partly broken away 20 and selected board-supporting strips being shown fragmentarily to better illustrate the supporting structure.

Fig. 2 is an enlarged perspective fragmentary view of one of the supporting members illustrating an anchor and a clamp for locking the surfacing sections in supported position.

Fig. 3 is a perspective view of a board supporting frame mountable on the supporting members shown in Fig. 2, some of the boards being re- 30 moved and one being shown fragmentarily to better illustrate construction.

Fig. 4 is a perspective view of one of the foot- 35 ing blocks of the jointed floor-supporting strips.

Fig. 5 is a perspective view of an abutment 35 block mounted at one end of a floor-supporting strip.

Referring more in detail to the drawings:

10 designates jointed elongated base or floor supporting members each comprising hingedly 40 connected end abutting pairs of parallel spaced strips 12 and 14 having substantial width and arranged on edge to form tying girders. Spacing blocks 15 are located between the strips of each pair and fixed thereto by pins 16 to hold the 45 strips together. Footing blocks or pillars 17, 18 and 19 are provided with central upwardly projecting tongues 20 insertable in the slots formed by the spaced strips and forming shoulders 22 on which the strips may rest.

50 The pillars 17 are mounted in similar ends of hinged pairs of strips, the pillars 18 are located at the joints, and the pillars 19 are located in slightly spaced relation with the opposite ends of the hinged pairs of strips to leave the ends of 55 the slots free for mounting anchor members or

lugs therein as later described. The spacing blocks 15 may be located in suitable position to serve as guides for locating the pillars.

The respective pillars are formed in suitable heights and shapes to engage portions of any 5 irregular supporting surface and level the girders.

The pillars 17 and 19 at the ends of the jointed girders are preferably removably attached to the strips by suitable means such as bolts 23. The 10 pillars 18 at the joints may be removably mounted on one of the strips of a pair to be carried by the pair when the girders are hingedly moved to be opened or folded, and the pairs of strips are disassembled or reassembled. The 15 tongues of the pillars 18 overlie the abutting end portions of the hinged strips and reinforce the joints.

The hinged connection between end-abutting 20 pairs of strips forming a girder is provided by 20 hinges 24 having straps mounted on the outer faces of aligned strips and pivotally connected by removable hinge pins 26 whereby the girder members may be folded laterally. Hinges are 25 preferably provided on both sides of the jointed 25 girder, whereby the pins of either of opposed hinges may be removed for folding the girder on the opposite hinge.

The anchor members above referred to comprise lug-like blocks of wood, illustrated in detail in Fig. 5, and including wedge-shaped bodies 28 resting on the ends of the strips and tongues 30 depending from the bodies into the ends of the slots between the pair of strips, to form vertical abutment faces 32 for one edge of flooring 35 sections mounted on the girders as presently described. The abutment lugs are secured to the strips by bolts 34.

Brackets 36 fixed to the upper edge faces of the strips at the opposite ends of the girders 40 from the abutments 28 support shafts 38 forming pivotal mountings for internally threaded sleeves 40, and screws 42 mounted in the sleeves have swivel heads 44 engageable with one side of the flooring to clamp the flooring against the anchor 45 block abutments.

The surfacing members of the floor include frames comprising parallel spaced bars such as 46 and 48, and sets of spacing blocks or strips 50 and 52 located between the bars and in staggered relation to permit clamping rods 54 to pass alternately behind and in front of adjacent blocks as best shown in Fig. 3.

The rods are straight and located in holes in the frame bars and have anchor means on oppo- 55

site ends engaging outer faces of outside bars of each frame, for example nuts 56 threaded on the ends of the rods which may be moved to tightly clamp the frame bars and spacing blocks in assembled relation.

The floor frames may consist of any desired number of parallel bars and sets of spacing blocks, and preferably will include at least four bars and two longitudinally spaced sets of blocks 10 to provide a floor section of substantial area that will be light in weight and held together to form a unit.

In Fig. 3 a frame is shown having five bars and two sets of spacing blocks. Attention is 15 called to the alignment of the first and third blocks and second and fourth blocks in the set exposed in the figure, whereby any tension or stress due to tightening of the nut on the bolt will be substantially equally distributed on both 20 sides of the bolt and distortion of the frame will be avoided. The bars and blocks comprise strips of wood having substantial width and arranged on edge, whereby the ends of the blocks abut the sides of the bars, and stiffen the structure against 25 vertical bending strains.

The plurality of bars comprising the type of frame shown in Fig. 3, are preferably arranged in groups of differently spaced bars whereby two bars at one side of a frame may be narrowly 30 spaced to add rigidity and form socket-like recesses into which the ends of adjacent frame members may extend.

Another type of floor frame is shown at the lower right hand corner of the floor in Fig. 1, 35 having the same width as the above described frame, and substantially equally spaced bars, including intermediate bars arranged in staggered relation with the intermediate bars of the aligned frame as clearly shown in the figure.

The inner ends of the intermediate bars of 40 each frame extend beyond the ends of side bars, and side bars of end abutting frames abut and are located on the relatively wide support formed by spaced strips 12 and 14 of the girders, and the 45 intermediate bars overlap and extend substantial distances beyond the supporting girders. The outer ends of all bars of a frame at one end of a floor assembly are aligned as indicated at the left end of Figs. 1 and 3.

Flooring is laid transversely on the frames including boards 60 having end edges registering 50 with the outer faces of the longitudinal side bars as shown in Figs. 1 and 3 for side edges of a floor assembly, and opposite ends projecting beyond 55 the opposite longitudinal side bar. Alternate boards are elongated to provide projecting tongues 62 and notches 64 between the tongues whereby the tongues of one floor section may be mounted in the notches of another to interlock 60 the edge abutting sections as shown in Fig. 1, and form a dovetailed floor.

Attention is called to the close proximity of the 65 ends of the shorter boards to the side bars of the frames whereby two frames may be laid relatively close together and the free ends of the boards will extend relatively short distances from the supports.

The dovetailed or interlocking relation of side 70 edge abutting floor sections therefore not only avoids a continuous crack in the floor but assures substantial support for at least half of the projecting board ends.

The rigidity of the longitudinal area of the 75 floor between adjacent side members of adjacent floor frames is further promoted by the use of

floor boards having edge grooves 66 and tongues 68 seated in the grooves whereby the tongues help to support the free ends of the boards.

The boards are preferably toe-nailed to the frame bars in the usual manner of laying floors, 5 to form flooring sections that may be laid on the girders and moved slidably thereon into desired position.

Attention is particularly called to the differential lengths of floor frames and assemblies of 10 surfacing boards nailed thereto, whereby adjacent longitudinally arranged floor sections overlap, as indicated in Fig. 1. The floor shown in this figure includes five pointed tying girders or 15 floor supporting members, and three longitudinal series of floor frames or sections arranged side by side. The intermediate series of floor sections has boards dovetailed with boards of the adjacent outer sections. The end floor sections of this intermediate series, shown at the right and left 20 ends of the figure, are shorter than the adjacent outside sections, and a long section extends between the two short sections to complete the middle series of floor sections. The joint 70 between end-abutting intermediate floor sections thus 25 lies between the ends of the adjacent outside floor sections, and the joint 72 between end-abutting outside sections lies between the ends of the long intermediate section.

It is apparent therefore that the joints of adjacent floor sections are staggered or broken, and that when the ends of floor boards of adjacent 30 floor sections are interlocked in dovetailed relation, the longitudinally aligned sections of a series will be held firmly together. The use of supplementary means such as bolts or cables for preventing separation of end abutting floor sections is thus obviated. When the laterally operating 35 clamps have been set to hold the series of sections against lateral displacement, the dovetailed 40 floor boards will securely lock all of the floor sections against displacement on the girders.

In order to square the assembly of girders and 45 assure parallelism and proper spacing therebetween, vertical sockets or holes 74 are formed in the strips 12 and 14 at numerous positions therealong, and downbent ends 76 of spacing bars 78 are mounted in selected sockets as clearly shown 50 in Figs. 1 and 2, and similar hook-like or anchor ends of diagonal bars 80 are mounted in other of said sockets to maintain the girders parallel.

Recesses 82 formed in the upper faces of the strips adjacent the sockets form seats for offsetting the bars below the plane of the upper surfaces of the girders to permit the floor sections 55 to lie on the girders and slide thereover.

The use of spacing and squaring bars further assures alignment of the abutment faces 32 of the anchor blocks in a vertical plane, so that the outer edge of an assembly of floor sections may accurately overlie the faces of the abutments and be pressed thereagainst by the clamps.

The spacing bars are preferably distributed along a pair of adjacent girders so that each member of a jointed girder will be connected by one or more bars with a member of an adjacent jointed girder. A single diagonal bar will be sufficient to square a pair of girders.

In using the invention the supporting girders 70 may be constructed and assembled with sufficient hinged arms or sections to provide a support for a floor of a desired area; in the illustrated application of the invention, each of the five floor supporting girders consisting of two arms. The 75

girders may therefore be folded into one-half the length of the extended base.

A suitable number of frames provided with surfacing boards fixed thereto may be arranged on spaced supporting girders, the projecting ends of frame bars extending beneath the boards of end-abutting floor sections and between the bars of said sections, and side frame bars in end abutting relation with the similar bars of end abutting sections.

The several frames may be moved longitudinal-
ly on the girders to effect assembly and to engage
the tongue of a board at the end of one section
in the groove of the board of the next end abutting
section, as suggested at 70 and 72 in Fig. 1. The
sections may be shifted laterally to effect inter-
locking engagement between abutting longitudi-
nal edges of the sections, so that each pair of end-
abutting sections may be locked together by the
dovetailed engagement of an adjacent single section
with said pair of sections.

The screws mounted on the outer ends of the
girders may then be operated to engage the heads
thereof with the outer faces of the side bars of
adjacent floor sections and operation of the
screws will shift the entire assembly of floor sec-
tions laterally into engagement with the anchors
at the opposite side of the assembly.

Operation of the screws will further press the
side edge tongues of floor sections into the notches
of edge-abutting sections and thus enforce the
interlocking relation of the sections and make
tight joints between edge-abutting sections.

What I claim and desire to secure by Letters
35 Patent is:

1. A sectional floor including a plurality of sup-
porting members each consisting of hinged sec-
tions and having aligning recesses at said hinge
connections, pillars supporting said members and
40 provided with tongues engaging in the aligning
recesses and overlapping said hinge connections
to prevent hinging movement of the supporting
members, a plurality of floor sections mounted on
45 said members, and means mounted on the sup-
porting members for retaining the floor sections
in abutting relation.

2. A sectional floor comprising supporting
members, each including a plurality of hingedly
connected sections comprising spaced strips and
50 means for retaining the strips in spaced relation,
pillars supporting said members and having por-
tions extending between said spaced strips at said
hinge connections and floor sections mountable
on said supporting members.

55 3. In a sectional floor including girders and
flooring mountable on the girders, anchors at one
end of the girders, and screws threadedly engaged

with the opposite end of the girders for clamping
the flooring to said anchors.

4. In a sectional floor, a surfacing member,
supporting means including a plurality of spaced
members, anchors fixed to one of the outer ends
5 of said supporting members, and means includ-
ing brackets mounted on the opposite ends of
said supporting members and screws threaded in
the brackets for clamping the surfacing member
to the supporting means.

10 5. In a sectional floor, supporting means in-
cluding a pair of girders and abutments at the
outer ends of the girders, a plurality of members
having portions engageable with the girders for
aligning the abutments, a floor section for mount-
15 ing on the girders to engage the abutments, and
means for holding the floor section in engage-
ment with the abutments.

20 6. A floor support including a girder compris-
ing a pair of sections having spaced portions at
the ends thereof, means hinging the sections in
abutting relation, and means closely engaging
between said spaced portions and overlapping
25 said hinged connection to prevent hinging move-
ment of the girder sections.

25 7. A floor support including a girder compris-
ing sections having spaced parallel members,
means for retaining said members in fixed spaced
relation, means for hinging the sections together,
and key means engageable between said members
30 and overlapping said hinge connection for pre-
venting hinging movement of said sections.

35 8. A floor support including a girder compris-
ing a pair of sections having spaced portions at
the ends thereof, means hinging the sections in
abutting relation, key means engaging between
said spaced portions at the hinged connection for
40 preventing hinging movement of said sections,
an anchoring member mounted on the end of one
of the sections, and a clamping screw member
mounted on the opposite end of the other section
for clamping a floor therebetween on the girder.

45 9. A floor support including a girder compris-
ing a pair of sections having spaced portions at
the ends thereof, means hinging the sections in
abutting relation, means engaging between said
spaced portions and overlapping the hinged con-
50 nection for preventing hinging movement of said
sections from extended abutting alignment, an
anchor having a depending tongue portion ex-
tending between the spaced portion at the outer
end of one of the sections, means for securing
55 said tongue to said section, and a clamping screw
fixed to the outer end of the other section for co-
operating with the anchor to clamp a floor there-
between on the girder.

CHARLES TRAMILL.
